UNITED STATES PATENT OFFICE

JOHN R. McDERMET, OF JEANNETTE, PENNSYLVANIA, ASSIGNOR TO ELLIOTT COMPANY, OF PITTSBURGH, PENNSYLVANIA, A CORPORATION OF PENNSYLVANIA

METHOD AND APPARATUS FOR TREATING LIQUIDS

Application filed September 5, 1924. Serial No. 736,087.

The present invention relates broadly to the degasification or deaeration of liquids, and more particularly to the treatment of feed water, such for example, as fed to boilers, economizers and the like, for effecting the removal of air and other entrained gases therefrom.

It has heretofore been proposed to utilize heaters of the "through" or "thoroughfare" type, both in condensing and non-condensing plants. It has also been proposed to use heaters of the "induction" type in a similar manner. Each of these types of heaters is well known commercially and each is recognized as having certain desirable characteristics. As disclosed in my copending applications, Serial No. 535,744 filed February 11, 1922 and Serial No. 582,151 filed August 16, 1922, very advantageous results may be produced by combining the two types of heaters in such manner that they both operate on the water being treated, each heater modifying the action of the other. This broad combination is covered in my applications referred to.

It will be understood that the term "thoroughfare" heater as used is definitive of the type of heater, preferably of the open contact type, having an excess of steam supplied thereto over and above that required to heat the water, both the heating steam and the excess steam entering the heater and the excess then passing to other connections. Its characteristic, therefore, is that there is a thoroughfare flow of steam through the heating chamber and this is the only constructional limitation which the designation of the heater carries with it. The term "induction" heater as used herein is definitive of the type of heater in which the steam is drawn thereto by the cooling effect of the water being heated. Preferably, the water in distributed condition is heated by contact with the steam. Its characteristic, therefore, is an induced flow which is generally proportionate to the work being done, and this is the only constructional limitation which the designation or description carries with it.

For purposes of a clearer understanding of the present invention, it may be pointed

out that the air content dissolved in water is partly a function of water temperature and partly a function of air tension in the atmosphere in which the water is agitated, as, for example, a heater. The minimum air tension, and therefore the ideal limit which can be secured in a heater of the open contact type in which steam is the heating medium, is obviously the air tension of the incoming steam. This is almost infinitesimal, particularly where the steam has been generated from degasified water. Any process of condensation by decreasing the condensable portion of the heating medium inevitably increases the noncondensable portion thereof, which is air.

From the standpoint of air tension, a thoroughfare heater is highly desirable, as it is able to approach the ideal limit referred to, provided the condensation of steam which occurs therein is substantially inappreciable. From an economical standpoint, however, a thoroughfare heater is not desirable in most power plants, because the uncondensed steam passing therethrough to other connections is ordinarily not recoverable.

An induction heater, on the contrary, operates in a different sense from a heat balance standpoint in that virtually all the steam coming to it is utilized, neglecting only the small amount which passes therefrom through the vent as a mixture with air. The induction heater, therefore, by condensing substantially all of the condensable portion of the vapor mixture coming to it, necessarily increases the proportion of air. This is undesirable from the standpoint of deaeration. From the heat transfer standpoint, however, without regard to deaeration the induction heater is much more efficient and to a large extent is the only commercially utilized heater in power plants.

I have discovered that it is possible to so combine these two types of heaters that the thoroughfare heater functions primarily for the purpose of deaeration, and the induction heater primarily for the purpose of heating the water before it passes to the thoroughfare heater. While the division of work may be varied as desired, it is preferable that the

thoroughfare heater be devoted to the duty of deaerating without doing substantially any heating, its capacity being based upon the fact that none of its tray surface is devoted to heating. In like manner, the induction heater should be devoted substantially entirely to heating duty without any attempt at the process of deaeration therein. This division of work is desirable for the obvious reason that if the major part of the heating medium is condensed in the induction heater and the major part of the heating is accomplished in this heater, virtually all of the heating medium coming to the thoroughfare heater will pass to the induction heater. By reason of this condition, the thoroughfare heater will have the advantages of the two fundamentals of high temperature with correspondingly low air solubility, and low air tension substantially equivalent to that of the heating medium.

From practical experience I have found that a combination of heaters of the character referred to gives most satisfactory performance and operates very advantageously at low initial air content. It is to be expected, however, that any air liberated in the thoroughfare heater ultimately arrives in the induction heater, since the two heaters are in series. Having arrived in the induction heater as one component of a mixture, its relative amount is increased due to the condensation in the heating process of the other component, which is steam. The air concentration in the induction heater limits the temperature of the water leaving the heater and accordingly the amount of air liberated in the deaeration process, to a certain degree, alters the temperature relationship between the two heaters and inevitably in a series effect, one heater of which is designed to do no heating, the failure of one of the heaters to heat imposes the heating duty on the other.

As the result of the foregoing, with high initial content in the water to be deaerated, it is impossible by a practical arrangement of sizes to so perfect the combination that the ideal upon which the design is based, namely that the thoroughfare heater do the deaerating and the induction heater the heating, is possible of attainment. The liberation of air depreciates the performance of the induction heater and when this performance is depreciated, the necessary heating capacity to attain the desired temperature must be assumed by the thoroughfare heater. The tray areas in the thoroughfare heater, however, are proportioned from the standpoint of deaeration, and any use of them for purely heating purposes depreciates the whole unit as a deaerator.

From a practical standpoint, it is necessary if the unit is to be a successful deaerator, to have the water arrive in the thoroughfare heater at substantially the temperature of

the steam, since no deaeration can be accomplished until such a temperature has been reached. The present invention has primarily for its object the provision in a combination of heaters of this character, of means to insure the desired temperature in the water supplied to the thoroughfare heater whereby the thoroughfare heater is relieved of the duty of heating, such as would be imposed thereon by the failure of the induction heater under normal conditions of high initial air content.

In the accompanying drawings, I have shown for purposes of illustration only, a preferred embodiment of the present invention, it being understood that the drawings do not define the limits of my invention, as changes in the construction and operation disclosed therein may be made without departing from the spirit of the invention or scope of my broader claims.

In the drawings:

Figure 1 is a diagrammatic side elevation, partly broken away, of one form of apparatus for carrying out the present invention;

Figure 2 is a vertical transverse sectional view through the apparatus illustrated in Figure 1, certain of the parts being shown in elevation; and

Figure 3 is a detail view, illustrating a slightly modified embodiment of the invention.

In carrying out the present invention, there may be provided an induction heater 2 having a manifold 3 for supplying the water to be treated, the outlets 4 from the manifold preferably discharging above a plurality of spray pans or other agitating means 5 over which the water is adapted to flow in cascade. The induction heater is preferably in superimposed relationship to a thoroughfare heater 6 having one or more vapor connections 6^a extending upwardly therefrom and into the induction heater. Liquid from the induction heater is adapted to flow into the thoroughfare heater through one or more connections 7, each communicating at one end with the bottom of the induction heater and at the other end discharging into the upper portion of the thoroughfare heater. The thoroughfare heater is also preferably provided with agitating means 8 herein illustrated as comprising a series of pans arranged to cause the entering liquid to flow through the vapor space of the thoroughfare heater in cascade.

Cooperating with the induction heater is a condenser 9 having a vapor outlet 10 which may communicate directly with the atmosphere or which may be in communication with an ejector 11, depending upon the conditions under which it is desired to operate the apparatus. The condenser has a water inlet 12 from which the water flows through one of the tube passes 13 and thence returns by an-

other tube pass 14 to the connection 15 leading to the manifold 3. Within the connection 15 is arranged a valve 16 adapted to be automatically operated in accordance with the liquid level in the thoroughfare heater by means of a float 17 operatively connected thereto. The vapor space of the induction heater has an operative connection 18 with the vapor space of the condenser 9.

Arranged within each of the water connections 7, preferably adjacent the end thereof, communicating with the induction heater 2 is a steam injector 19 which may comprise a plurality of tubes communicating with a header 20 having a steam inlet 21. Preferably these tubes extend into the connections 7 in such manner as to discharge steam in the direction of the flow of water therethrough. It is well recognized that any attempt to inject steam below the surface of a body of water meets a resistance equal to the hydrostatic head of the submerged orifice through which the steam is to be discharged. If, however, the steam is discharged into a pipe line in which the direction of the steam discharge and the direction of the water flow are the same, the two factors will be mutually accelerating. This is due to the fact that the steam in the process of condensation contributes its velocity to the water, and the water by its initial velocity contributes to the velocity of the steam. The velocity of the water decreases the pressure of the steam necessary to secure the injection because of this mutual accelerating action. By reason of the construction herein illustrated, therefore, it is possible to utilize a comparatively low pressure steam injector, as well understood in the art.

In addition to the advantages from a heating standpoint, this arrangement also has the advantage that it is readily accessible and can be repaired without the necessity of going into the interior of either of the heaters. During the operation of the apparatus there will usually be a solid body of water within the connections 7, thereby insuring efficient heat interchange by this steam injection. It furthermore makes it unnecessary to utilize any of the capacity of the induction heater for the concentrating of a solid body of water and insures a less expensive initial cost for the reason that the induction heater may be designed solely from the standpoint of heating surface.

In practice, the steam for operating the injector nozzles approximates about 12 inches of mercury and may be derived from a separate source of steam supply or by a reducing back pressure valve incorporated in the steam supply line, this valve being of a pressure loaded type so as to impose sufficient pressure on the line to create the temperature differential of approximately 12 inches of mercury to operate the jet and permit any surplus of steam amounting in practice to approximately 98 per cent to pass onward and enter the

thoroughfare heater and fulfill its normal function.

In the accompanying drawings I have illustrated the latter method of steam supply comprising a main inlet 22 leading directly to the thoroughfare heater 6 and having therein a differentially unbalanced valve 23 which may be loaded in any desired manner, as by a spring 24. Steam may be supplied to the valve 23 through a connection 25 having a bypass cooperating with the connection 21 for supplying the steam to the auxiliary heating means within the connections 7.

In some cases it may be desirable to operate the apparatus at a temperature corresponding to a pressure which is below atmospheric pressure. In such cases the condenser 9 will tend to withdraw the released vapors and gases from the apparatus and thereby maintain the desired thermal conditions 85 therein. It will be understood that for this purpose the particular design of the condenser may be changed in accordance with the conditions under which it is desired to operate the apparatus. By utilizing such a condenser, not only are the desirable thermal conditions maintained within the heater, but the sensible heat of the released vapors and gases is conserved and imparted to the incoming water for preheating the same.

When operating under subatmospheric conditions as just described, it will be obvious that there may exist within the steam supply connection 25 a steam pressure which is also subatmospheric. As the present state of the art dictates the advisability of maintaining steam supply lines under a pressure which is at least atmospheric, it is undesirable to have the pressure conditions within the connection 25 transmitted to the steam supply line 26. 105 If such conditions were maintained in the steam supply line, there would be a corresponding tendency toward air infiltration which would not only contaminate the water but would impair the efficiency of the apparatus. In order to prevent such an undesirable condition, there may be provided within the line 26 a balanced valve structure 27 having a piston or diaphragm 28 subjected on one side to atmospheric pressure through 110 a port 29 and on the other side to pressure within the connection 25 through a passage 30. The pressure within the connection 25 may be adjustably augmented by a loading spring 31 whereby the desired operating conditions of the valve will be insured. In this manner either atmospheric or subatmospheric conditions may be maintained in the supply line 26, irrespective of the conditions existing within the apparatus or the connection 25. 125

With contemplated developments in the art, the use of a balanced valve in the steam supply line may be rendered unnecessary as the supply of steam at subatmospheric pressures may be made possible. It will be understood 130

therefore that while such a valve, or some equivalent means, is both necessary and desirable in certain installations, the operation of the present apparatus is not necessarily dependent thereon in certain cases.

If desired, I may substitute for the balanced valve a thermostatic valve operated in accordance with the temperature within the induction heater, as disclosed in my copending application Serial No. 582,151, hereinbefore referred to. Such a modification is illustrated in Figure 3. In this figure there is illustrated a valve 32 having a controlling element 33 within the induction heater, preferably adjacent the bottom thereof, so as to be within the comparatively small body of liquid maintained therein by reason of the location of the inlets to the connections 7. In this manner the admission of steam to the thoroughfare heater is regulated in proportion as the admission of water to the induction heater varies the temperature therein. In accordance with the present state of the art, it is customary to withdraw the exhaust steam, which is almost universally employed as heating steam for boiler feed water, from the auxiliaries which produce it at substantially atmospheric pressure. It may be desirable, however, as before referred to, to effect deaeration at temperatures below atmospheric, for example between 140° and 212° F. If atmospheric steam in excess is admitted to the thoroughfare heater, it will obviously be impossible to maintain the desired low pressure temperature therein while, on the other hand, if a deficiency only of steam is available, the pressures would drop below atmospheric and a vacuum would be produced on the valve 32. Without the valve this pressure would be transmitted to the supply line with the objections before pointed out. This makes it only necessary to protect the apparatus per se against air infiltration. The thermostatic valve, where employed, further constitutes an automatic means for preventing undue condensation of steam within the thoroughfare heater, such as would impair its operating efficiency.

If it were possible in commercial practice to obtain steam for heating purposes entirely free of dissolved gases, the operation of an apparatus of this character would be greatly simplified. As this is not possible, however, the provision of the vents or connections 18 for the induction heater for the purpose of removing non-condensable gases therefrom is necessary. It is impossible in condensation work to secure an entirely steam-free vent mixture and these vents therefore conduct a mixture of steam and air. Since the induction heater is of necessity a good heating means but an imperfect condensing means, this vent may at times carry away a very considerable portion of steam which without the condenser 9 would represent a loss. The

ejector 11 cooperating with the condenser by its aspirating action induces a steam flow into the thoroughfare heater, through such heater and then into the induction heater, the condensable portion being condensed within the condenser and the heat thereby recovered. 70

It is desirable that the heat exchange means comprising the induction heater, the thoroughfare heater and the condenser shall all operate under a vacuum corresponding very closely to atmospheric pressure, minus the vapor tension of the water in the induction heater. The condenser is therefore further desirable, as it obviates the necessity of providing an ejector having an air ejecting capacity large enough for aspirating a large quantity of steam from the induction heater. The condenser by its action secures economy in ejection capacity. If the condenser was of sufficient capacity to accomplish its duty 80 automatically, there would be a rush of steam through the thoroughfare heater into the induction heater and thence into the condenser. By making the condenser of proper size, there is provided an automatic regulation in 90 that if its heating duty is exceeded, the ejection capacity of the ejector will be automatically diminished by reason of the overload of steam received thereby. It will be apparent that the value "ejection capacity" 95 as used herein its rated in terms of air or non-condensable gas removal where a reduction in ejection capacity, as referred to, will automatically lower the vacuum and increase the absolute pressure in the induction heater. 100 As the pressure in this heater rises, the temperature will also tend to rise, thereby tending to limit the further admission of steam to the thoroughfare heater either through the balanced pressure valve or the thermostatic valve. 105

During the operation of the apparatus, cold water enters the condenser and recovers the heat from the vented mixture and then passes into the induction heater flowing therethrough in broken up condition and then entering the thoroughfare heater, where it is again broken up. This flow is in a downward direction, while the heating medium enters the thoroughfare heater and flows in 110 an opposite direction. This countercurrent flow is very desirable from a standpoint of efficient heat transfer. The flow of water is automatically controlled by the valve 16 in accordance with demands on the apparatus 120 through the offtake 34.

As the induction heater and its associated parts tend to prevent any increase in the partial air tension within the thoroughfare heater, it is to be expected that under certain 125 conditions the air concentration in the induction heater may reach such a point as to interfere with the desired temperature conditions therein. In such cases the admission of steam through the auxiliary heating means 130

19 enables the desired temperature conditions to be maintained and the water supplied to the thoroughfare heater without throwing any additional load onto the thoroughfare heater such as would impair its efficiency from a deaerating standpoint. In actual practice an amount of steam will be supplied to the auxiliary heating means sufficient to at least raise the temperature of the water 10 passing through the connections 7 by an amount equal to the depression in the induction heater by reason of increased air concentration therein.

In order to provide a continuous record 15 of temperature, and to provide for accurate regulation of temperature, there may be provided an indicating or recording thermometer 35 connected to both the induction and thoroughfare heaters.

20 The accompanying drawings may be considered as largely diagrammatic for the purpose of illustrating the invention. For the sake of a clear understanding, I have illustrated the heaters as comprising separate 25 chambers. It will be obvious, however, that the same operation and results would be obtained by providing a common enclosing shell with a thoroughfare tray section or compartment and an induction tray section 30 or compartment. In such a construction the entering water would first preferably pass, as illustrated, through the vent condenser as the cooling medium for the vented vapors which leave the induction compartment 35 or heating section of the deaerating apparatus; this water would be distributed by the tray section in the induction compartment. The entering steam would pass horizontally through the lower or air separating 40 tray compartment. In passing through this compartment, the steam sweeps the air with it and then rises vertically through the port or ports provided to the heating or induction compartment. The water in turn flows 45 through the connections provided into the lower or deaerating compartment, whereby a counter flow of air and water is obtained.

The advantages of the present invention 50 arise from the provision broadly of a combination of two heaters with connections for compensating for any depression in the heater primarily devoted to a heating duty.

Further advantages arise from the provision of means for automatically maintaining 55 the temperature of water supplied to a thoroughfare heater sufficiently high to make it unnecessary for the thoroughfare heater to accomplish any substantial heating duty.

Further advantages arise from the provision in an apparatus of this character of 60 means permitting operation at any desired temperature conditions without danger of air infiltration into the steam supply line and without the possibility of steam waste from the apparatus.

I claim:

1. In the method of treating liquid, the steps consisting in successively heating the liquid in broken up condition, and further heating the liquid intermediate said successive heating stages by the injection of a heating medium into the liquid while in a solid body. 70

2. In a feed water heater, a thoroughfare heater having a steam inlet and a steam outlet, a connection for feeding heated water to said heater, means controlling the steam supply to said heater through said inlet to prevent increase in air tension therein, heating means inducing a steam flow through the heater and supplying heated water to said connection, and means in said connection for supplying additional heat to the water therein. 75

3. In a feed water treating apparatus, a thoroughfare heater, an induction heater for delivering heated water thereto, a vapor connection between said heaters, a water connection between said heaters, and means for injecting steam into the water passing from the induction heater to the thoroughfare heater through said water connection. 80 85

4. In an apparatus for heating and deaerating water, a plurality of heating means in series, a pipe connection for passing heated liquid from one of said heaters to the next heater of said series, and means in said pipe connection for further heating the water flowing therethrough. 90 95

5. An apparatus for deaerating liquids, comprising two separate sets of liquid agitating and distributing trays over which the liquid passes in series, means for supplying steam to the systems in series with the steam supply initially to the system last receiving liquid, and heating means intermediate the systems for compensating for temperature depression in the first system. 100 105

6. An apparatus for deaerating liquids, comprising two liquid agitating and distributing systems over which the liquid passes in series, means for supplying steam to the systems in series with the steam supply initially to the system last receiving liquid, and heating means intermediate the systems for injecting steam into the liquid in the direction of its flow. 110 115

7. An apparatus for deaerating liquids, comprising two liquid agitating and distributing systems over which the liquid passes in series, means for supplying steam to the systems in series with the steam supply initially to the system last receiving liquid, separate liquid and vapor connections between said systems, and heating means intermediate the systems for injecting steam into the liquid passing through the liquid connection to maintain a constant temperature of liquid to the last system irrespective of initial air content of the liquid. 120 125 130

8. Apparatus for deaerating liquids, comprising a lower tray section, an upper tray section, connections for feeding liquid into the upper tray section and thence to the lower tray section, connections for supplying steam to the lower tray section and thence to the upper tray section, and means intermediate the tray sections for varying the temperature of the liquid during its passage from one section to the other.

10 9. Apparatus for deaerating liquids, comprising a lower tray section, an upper tray section, connections for feeding liquid into the upper tray section and thence to the lower tray section, connections for supplying steam to the lower tray section and thence to the upper tray section, and means intermediate the tray sections for injecting steam into the liquid leaving the upper tray section.

15 10. Apparatus for deaerating liquids, comprising a lower tray section, an upper tray section, connections for feeding liquid into the upper tray section and thence to the lower tray section, connections for supplying steam to the lower tray section and thence to the upper tray section, and supplemental heating means intermediate the tray sections.

11. Deraerating apparatus, comprising an induction section, a thoroughfare section, means for producing a liquid flow through said sections in one direction and a steam flow through said sections in a counter direction, and means for injecting steam into the liquid in the direction of liquid flow during its passage from one section to the other.

12. Deraerating apparatus, comprising an induction section, a thoroughfare section, means for producing a liquid flow through said sections in one direction and a steam flow through said sections in a counter direction, supplemental heating means for the liquid flowing from one section to the other, and liquid distributing means in each of said sections.

13. Deraerating apparatus, comprising an induction section, a thoroughfare section means for producing a liquid flow through said sections in one direction and a steam flow through said sections in a counter direction, means for injecting steam into the liquid during its passage from one section to the other, and liquid distributing means in each of said sections.

14. Deraerating apparatus, comprising an induction section, a thoroughfare section, means for producing a liquid flow through said sections in one direction and a steam flow through said sections in a counter direction, means for injecting steam into the liquid in the direction of liquid flow during its passage from one section to the other, and liquid distributing means in each of said sections.

15. In a feed water heating system, an induction heater, a thoroughfare heater, a water connection between said heaters constitut-

ing a water concentrating space for the induction heater, means supplying heat to the water in said storage space, means for supplying steam initially to the thoroughfare heater, and means for supplying water initially to the induction heater.

16. In a feed water heating system, an induction heater, a thoroughfare heater, a water connection between said heaters constituting a water concentrating space for the induction heater, means for supplying steam initially to the thoroughfare heater, means for supplying water initially to the induction heater, and means delivering heating steam to the water in said connection.

17. In a feed water heating system, an induction heater, a thoroughfare heater, a water connection between said heaters constituting a water concentrating space for the induction heater, means for supplying steam initially to the thoroughfare heater, means for supplying water initially to the induction heater, and means for injecting heating steam into the water in the direction of its flow.

18. In the method of treating liquid, the steps consisting in heating a liquid by the condensation of a heating medium, passing the heated liquid into the vapor space of a second heater, heating the liquid during its passage to the second heater before it reaches said vapor space to an amount required to compensate for temperature depression caused by air concentration during the first heating, and controlling the supply of liquid in accordance with demands for treated liquid.

19. In the method of treating liquid, the steps consisting in heating a liquid, passing the heated liquid to a second heater, and supplying steam to the liquid during its passage to the second heater under such conditions that the velocity action of the steam and water is mutually accelerating.

20. In the method of treating liquid, the steps consisting in heating a liquid in a heater by the condensation of a heating medium, passing the heated liquid to a second heater, further heating the liquid therein by the condensation of a heating medium, and compensating for the decreased heating efficiency of the first heater caused by increased air concentration therein, by injecting a heating medium into the liquid in the direction of its travel during its passage from one heater to the other.

21. In the method of treating liquid, the steps consisting in heating a liquid by the condensation of a heating medium, passing the heated liquid to a second heater, and heating the liquid during its passage to and before it enters the second heater to an amount required to compensate for temper-

ature depression caused by air concentration during the first heating.

22. In the method of treating liquid, the steps consisting in supplying the same to a heater and heating the same therein by an induced flow of heating medium substantially proportional to the work being done, passing the heated liquid to a second heater, passing the heating medium for the first heater through the second heater, maintaining a relatively low air tension in the second heater by the first heater, and heating the liquid during its passage to and before it enters the second heater to an amount required to compensate for temperature depression in the first heater caused by increased air concentration therein.

23. In the method of treating liquid, the steps consisting in supplying the same to an induction heater, heating the same therein, passing the heated liquid to a thoroughfare heater through a defined liquid flow path, passing the heating medium from the thoroughfare heater to the induction heater through a separate defined flow path and maintaining a relatively low air tension in the thoroughfare heater by the induction heater, and heating the liquid in said defined liquid flow path during the flow of the liquid from the induction heater to the thoroughfare heater.

24. Apparatus for deaerating liquids, comprising a plurality of heating means in series, a pipe connection for passing heated liquid from one of said heaters to the next heater of said series, and heating means in said pipe connection for further heating the water flowing therethrough, said heating means having a steam connection leading directly thereto.

25. Apparatus for deaerating liquids, comprising a plurality of heating means in series, a connection for passing heated liquid from one of said heaters to the next heater of said series, and heating means in said connection for further heating the water flowing therethrough, said heating means having a steam connection leading directly thereto for discharging the steam into said liquid in the direction of liquid flow through said connection.

26. Deaerating apparatus, comprising separate heating chambers, water connections for said chambers, steam connections for said chambers independent of the water connections, and means for increasing the temperature of the water flowing through one of said water connections.

27. Deaerating apparatus, comprising an induction heater having a plurality of trays therein, a thoroughfare heater having a plurality of trays therein, a water connection from the induction heater to the thoroughfare heater, a vapor connection from the thoroughfare heater to the induction heater,

and means for increasing the temperature of the water passing through said water connection.

28. Deaerating apparatus, comprising an induction heater having a plurality of trays therein, a thoroughfare heater having a plurality of trays therein, a water connection from the induction heater to the thoroughfare heater, a vapor connection from the thoroughfare heater to the induction heater, and means for increasing the temperature of the water passing through said water connection, said means comprising a steam nozzle structure discharging into the water in the direction of water flow through said connection.

29. Deaerating apparatus, comprising a heating chamber having a plurality of trays therein, a second heater having a plurality of trays therein, means for delivering water to said trays, means for heating the water in its passage over said trays, a water concentrating space intermediate said trays for water heated in the first heater, and means for further heating water in said space during its passage to the second heater.

30. In the method of deaerating, the steps comprising subjecting the water to contact with steam in a plurality of stages and supplying heating steam intermediate certain of said stages to heat the water and to increase its velocity.

31. Deaerating apparatus, comprising a thoroughfare heater, an induction heater, said thoroughfare heater having a vapor space and a liquid space, means for supplying steam to both of said heaters, means for passing the liquid from said induction heater to the vapor space of the thoroughfare heater, and means for heating the liquid during its passage to and prior to its entry into said vapor space.

32. Deaerating apparatus, comprising an induction heater and a thoroughfare heater, a vapor connection between said heaters, a liquid connection between said heaters, and means cooperating with said liquid connection for supplying additional heat to the water passing therethrough.

33. In the method of deaerating water, the steps comprising passing the water in series through an induction heater and a thoroughfare heater, continuously passing substantially all of the steam from the thoroughfare heater into the induction heater, and supplying additional heat to the liquid intermediate the induction heater and the thoroughfare heater.

In testimony whereof I have hereunto set my hand.

JOHN R. McDERMET.
